INVENTOR

I. R. FLEMING,

BY *John Morris*
ATTORNEY.

Patented June 23, 1925.

UNITED STATES PATENT OFFICE.

IVAN RUPERT FLEMING, OF AINSDALE, ENGLAND.

SEA ANCHOR.

Application filed January 3, 1924, Serial No. 684,238. Renewed April 28, 1925.

To all whom it may concern:

Be it known that I, IVAN RUPERT FLEMING, a subject of the King of England, and residing at 10 Mossiel Avenue, Ainsdale, in the 5 county of Lancaster, England, have invented certain new and useful Improvements in Sea Anchors, of which the following is a specification.

This invention has reference to sea 10 anchors, and has primarily for its object and effect to provide a sea anchor for life boats and other craft, which, while it is of relatively large size when in use, as is often required, occupies a relatively small space in 15 the boat or craft in which it is carried.

The anchor is expansible and collapsible or foldable, and consists of a body of canvas or equivalent flexible material, and means such as ribs, links, levers, or the like, for 20 connecting the body with the said stem or member, by which the body can be expanded and contracted; and further the anchor is adapted to be expanded and open by the water when being towed. Thus, when the 25 body is not in use, and is to be stowed, it is collapsed, and will occupy very little space; while when it is in actual operation and being towed, it is expanded at one end by the pressure of water acting on it.

In some cases the edge of the body is held 30 by the links or the like, or its opening is limited or controlled by same; and in some cases guys or lines may connect the edge of the body or the outer ends of the arms, ribs, 35 levers, or the like, with the stem or central member.

In one construction, the stem is telescopic, and to its outer end, or to a disk thereon, one end of the body is attached, whilst the 40 inner ends of the ribs, levers or arms, are attached to a head on one end of the other member of the stem; their outer ends being attached to the outer or front edge of the body. In some cases a stop is provided on 45 one part of the members of the telescopic stem by which the limit of movement of the one member in relation to the other, is controlled, so that when the body is expanded or opened to the required degree and inclination, it cannot move further, so thus its degree of opening is limited; and the part of 50 the stress on the body is transmitted to the

stem, or the fore or towing end, that is, the end to which the anchor line is connected.

The invention is illustrated in the accompanying drawings, which show two modifications of the anchor.

In the drawings, Figure 1 is a sectional elevation showing one modification; Figure 2 a sectional elevation showing another; 60 whilst Figure 3 is a detail.

In the drawings, the anchors are shown open or expanded as in actual operation; the dotted lines in Figure 1 showing the position of the parts when the anchor is 65 collapsed, and in the condition of stowage.

The body which is made of canvas or flexible material, is marked 1, and 2 are the radial arms, to the outer ends of which the front or mouth edge of the canvas or flexible 70 material is to be attached. In Figure 1, 3 is the stem to which the inner ends of the arms are hinged, and 4 are ties or guys of rope or the like, by which the outer ends of the arms 2 are connected to the front or 75 towing end of the stem 3.

In the case shown in Figure 1, the stem is telescopic, and to the stem part 3 the inner 80 ends of the arms 2, and the guys or ropes 4 are connected; while to the other part 3^x the rear end of the body canvas or flexible material 1 is attached; the attachment in the case shown being to a disc 5, on the end of the stem part 3^x. A pulley block and tackle is attached to the stem for operating in connection with and controlling an oil bag for distributing oil on to the sea for smoothing it; or to which a tripping guy from the boat may be connected for hauling the rear 85 end towards the boat when desired, as hereinafter described.

The inner end of the arms 2 are connected to the tubular stem part 3 by means of a jawed ring 6 fixed thereon; and the inner end of the ropes or guys 4 are connected to 90 eyes in a disc 8, on the opposite end of the stem 3, to which end also the hauling swivel eye or ring 9 is attached.

In the collapsed position, the arms 2 with the discs 6, and the ring 8, will take the 100 position shown in the dotted lines.

In this case, the strain on the body caused by the water is taken partly by the leading edge of the fabric 1, which may be rein-

forced, and partly by the cords 4. Or, a stop may be provided on the tube members 3^x and 3 so as to limit the movement forward of the ring 6 and tube 3, when the anchor is thrown into the sea and towed, and so outward opening of the mouth is controlled.

The collapsed position of the arm 2 is shown in dotted lines in Figure 1, so that an opening would exist at the mouth of the canvas when folded, whereby when it is put into the sea, and is towed or pulled on, the water enters it, and, automatically causes the body to expand and open.

Water is permitted to pass through the anchor when in action by providing the end disc 5 with a number of holes 11, which present, a substantial area for the escape of water, and a constant flow through the anchor. This flow has a steady and generally improved effect in connection with the sea anchor.

In the case of a bag of oil for smoothing the sea being used in connection with an anchor, a pulley block 12 may be fastened or secured to the swivel eye or ring 10 on the back end of the anchor; the oil bag 13 being secured in any suitable manner to the falls 15 the two ends of which may be joined together so as to form an endless rope, the falls passing through the block 12 and back to the boat, so that the bag may be paid out, and put in the sea in advance or beyond the anchor. This rope and gear also serve as a tripping gear, as when hauled in, the anchor's position becomes reversed in the sea, the end ring 10 being then forward, next the boat; and in this position the anchor will close and collapse of itself, and can be easily taken into the boat; or the anchor may be tripped by hauling in both the ropes at the same time.

An anchor for use in connection with ordinary ships' life boats, may have a body of about 4 to 6 feet in diameter, and about the same length or longer.

In some cases, the ribs may run from the front or open end of the canvas or fabric to the back end, and if desired the anchor can be folded by hinging the parts of the arms and stem.

In the modification shown in Figure 2, the stem portion 3 is in the form of a rope, say of textile fabric or metal; and the tubular part 6 to which the arms 2 are attached and hinged, will, in use, engage a knob 3^{xx} on the end of the rope.

The ring 8 in this case, to which the guys or ropes 4 are connected, slides on the stem 3, and engages a stop 12, when the anchor is expanded; and thus the outward movement of the arms 2 is limited and regulated, and strain does not come on the edge of the canvas.

In addition to or instead of outlet holes being provided in the disc 5, they may be

provided in the back end of the body 1 itself; also ropes may be attached to the body 1, and extend between the disc 5 and the outer edge of the body.

In some cases, to keep the mouth of the anchor open when in its closed or folded condition, a disc may be provided on the stem 3, so that the arms 2 cannot move beyond the edge of this disc inwards.

In some cases the ribs 2 themselves, as well as the stem 3, can be hinged or folded in their centres, so as to fold up more compactly.

When the anchor is folded, it may be bound about with the tripping line or tackle 80 above referred to; and so constitutes a compact and small body, occupying a very small space; and can be readily stowed within an oiled or waterproof cover to protect and preserve it, so that at all times it will be in good sound condition, and available for immediate use; and furthermore when stowed it will take very little space and be out of the way of the occupants of the boat.

A sea anchor of the kind concerned, of 90 relatively large size, can thus be used in a life boat, as it occupies very little storage space; and therefore the use of a relatively large powered anchor is rendered feasible, and so a boat may be prevented from drifting very much, from the position it is desired to remain in; and, furthermore, the tripping line being in the form of endless falls, with oil bag attached, ensures that the bag can always be let go with the sea anchor, 100 and it can be readily hauled inboard for refilling if desired.

Buoyancy devices may be used in connection with the anchor such as cork, or air vessels, to keep it at the required depth of immersion.

What is claimed is:—

1. A sea anchor including a hollow stem, a plurality of arms pivotally connected at one end to the stem, a canvas body having one edge connected to the outer ends of said arms, a rod slidable in the stem and forming a continuation thereof when extended, a disc secured upon the rod and formed with openings, the remaining edge of the body being connected to the peripheral edge of said disc, and guy ropes extending from the free ends of the arms to the forward end of the stem.

2. A sea anchor including a hollow stem, a plurality of arms pivotally connected at one end to the stem, a canvas body having one edge connected to the outer ends of said arms, a rod slidable in the stem and forming a continuation thereof when extended, a disc secured upon the rod and formed with openings, the remaining edge of the body being connected to the peripheral edge of said disc, guy ropes extending from the free ends of the arms to the forward end of the stem, a ring arranged on the end of the rod

beyond the disc, a pulley block engaging said ring, an endless rope having one strand passed over the pulley block, and an oil bag connected to said rope, whereby the oil bag 5 may be permitted to drift beyond the anchor or drawn into contact with the pulley block, said rope serving as a tripping gear for the anchor.

In testimony whereof I have signed my name to this specification in the presence of 10 two subscribing witnesses.

IVAN RUPERT FLEMING.
